ROLLER GUIDE

Charles J. Gaykowski, Cleveland, Ohio

Application March 12, 1945, Serial No. 582,341

2 Claims. (Cl. 80—51)

1

This invention relates to a roller guide and more particularly to such a guide for use in guiding strip into a cold rolling mill, the guide maintaining the travel of the strip in a straight line substantially perpendicular to the axis of the rolls and at the same time preventing any lateral movement of the strip out of its original position during the rolling operation. Unless guides of some sort are used to bear against the edges of the strip and thus control its direction of travel into the work rolls the strip tends to travel laterally back and forth across the roll faces and thus set up rolling conditions which are not uniform. The aforementioned conditions are more likely to occur in a single stand mill than in a tandem mill in which certain amount of back tension is applied between stands. However, the guide can also be used to guide strip into continuous processing machines. At present, two general types of guides are normally used. The one type uses stationary guide plates made of brass or similar soft material and since the plates are softer than the strip, they become worn and must be continually replaced. The strip also cuts into the stationary plates and picks up small amounts of brass which are rolled into the strip by the mill. Roller guides consisting of several individually supported rollers are also used, but the rollers often stick or jam on their supporting axles due to the impossibility of lubricating them because of the fear of splashing the lubricant on the strip material which in some cases is very undesirable. The rollers may have a V-shaped periphery in which case excessive wear occurs at the bottom of the V.

It is an object of my invention to provide a roller guide wherein the rollers are supported for individual rotation and also for movement in the direction of travel of the guided material.

This and other objects will be more apparent after referring to the following specification and attached drawings, in which:

Figure 1 is a plan view of the guide in place on a rolling mill;

Figure 2 is a sectional view taken on the line II—II of Figure 1;

Figure 3 is an enlarged sectional view taken on the line III—III of Figure 1;

Figure 4 is a side elevation of the roller guide unit;

Figure 5 is a sectional view taken on the line V—V of Figure 4; and

Figure 6 is a sectional view taken on the line VI—VI of Figure 4.

Referring more particularly to the drawings,

2

reference numeral 2 indicates the housing of a conventional two-high cold rolling mill having rolls 4 journaled therein. On the entry side of the mill there is the usual guide table 6 having a groove 8 therein extending transversely of the path of travel of the strip S to the rolls 4. A conventional guide box 10 is fastened to the table 6 by means of studs 12 which pass through flanges 14 at each side of the guide box and are threaded into tapped holes 16 in the table 6. The roller guide of my invention consists of two units 18, one on each side of the strip and adjusted and positioned in the guide box 10 to bring the rollers into contact with the edge of the strip. For this adjustment, any conventional means may be used and, as shown, consists of opposed wedges 20 and shims 22 which bear against the guide unit 18. By moving the wedges 20 relative to each other, the guide unit 18 is moved to the desired position and locked in such position by means of locking studs 24.

Each guide unit includes a bottom plate 26 having a recess 28 in the upper portion thereof and lugs 30 extending downwardly therefrom and which are received in groove 8 to prevent longitudinal movement of the guide. A top plate 32 having a recess 34 in the bottom portion thereof is connected to the bottom plate 26 by a center plate 36. The center plate is received in the recesses 28 and 34 and is spaced from the walls thereof to form an endless race 38 in each of plates 26 and 32. The center plate 36 is provided with three threaded openings 40 for receiving flat headed screws 42 which pass through countersunk openings in the top and bottom plates to fasten them together. Dowel pins 46 are driven into aligned openings 48 in plates 26, 32 and 36 to provide additional fastening means and to insure alignment of the parts. Wearing strips 50 are positioned in the bottom of recesses 28 and 34 to provide wearing surfaces for hardened rollers 52, which are mounted in the races 38 and extend around the center plate 36, as best shown in Figure 5. It will be seen that the guide permits individual rotation of the rollers and also mass movement thereof around the center plate in the direction of travel of the strip, this resulting in a continuously changing bearing surface made up of a multiplicity of successive points of contact which increases the life of the guide.

While one embodiment of my invention has been shown and described, it will be apparent that other adaptations and modifications may

be made without departing from the scope of the following claims.

I claim:

1. A guide comprising a bottom plate having a recess in the upper portion thereof, a top plate having a recess in the lower portion thereof, a center plate extending between and fastened to said top and bottom plates in said recesses, said center plate being spaced from the walls of the recesses to form an upper and a lower endless race therearound, and a plurality of elongated rollers around said center plate mounted for free movement with their upper and lower ends received in said upper and lower races respectively.

10

2. A guide comprising a bottom plate having a recess in the upper portion thereof, a top plate having a recess in the lower portion thereof, a center plate extending between and fastened to said top and bottom plates in said recesses, said top plate being removable from said center plate, said center plate being spaced from the walls of the recesses to form an upper and a lower endless race therearound, and a plurality of elongated rollers around said center plate mounted for free movement with their upper and lower ends received in said upper and lower races respectively.

CHARLES J. GAYKOWSKI.
